UNITED STATES PATENT OFFICE.

JOHN D. SMITH, OF BONHAM, TEXAS, ASSIGNOR OF ONE-HALF TO GEORGE W. RAGSDALE, OF SAME PLACE.

REVOLVING CABINET.

SPECIFICATION forming part of Letters Patent No. 568,681, dated September 29, 1896.

Application filed February 17, 1896. Serial No. 579,568. (No model.)

To all whom it may concern:

Be it known that I, JOHN D. SMITH, a citizen of the United States, residing at Bonham, in the county of Fannin and State of Texas, 5 have invented new and useful Improvements in Revolving Cabinets, of which the following is a specification.

This invention relates to revolving cabinets adapted to contain general articles of 10 merchandise and household supplies, and has for its object to provide a cabinet of the character described that shall constitute a counter or a part of the same, or that may be used as a kitchen-table, and at the same time serve as 15 a convenient receptacle for the safe storage of general articles of merchandise and household supplies, which shall be maintained in a clean and fresh condition and be easy of access.

20 To these ends my invention consists in the features and in the construction, combination, or arrangement of parts hereinafter described, and pointed out in the claims following the description, reference being had to the 25 drawings forming a part of this specification, wherein—

Figure 1 is a perspective view of my improved cabinet. Fig. 2 is a vertical sectional view thereof. Fig. 3 is a top plan view of the 30 revolving compartment-case. Fig. 4 is a detail perspective view illustrating the manner of assembling and securing together the partitions, and Figs. 5 and 6 are respectively a perspective view and a detail view of a modification.

35 Referring to said drawings, the numeral 1 indicates a counter or table top, beneath which is arranged my improved cabinet. The cabinet is inclosed in a frame or housing consisting of a rectangular top frame 2 and a similar or corresponding bottom frame 3, said frames at their corners being united by corner-posts 4, and to said top and bottom frames are rigidly secured cross-bars 5 and 6. These 40 frames and cross-bars may conveniently form a part of the counter usually forming a part of the fixtures of a store or shop, or they may form part of a table.

45 Between the frames 2 and 3 is disposed a revolving cabinet 7, which is preferably octagonal in shape, and is constructed by join-

ing together, at right angles to each other, two slotted partitions 8 and 9, and equidistant between said partitions 8 and 9 are disposed partitions 10, which at their inner ends 55 are attached to battens 11. The battens 11 are suitably secured between the converging ends of the partitions 8 and 9, and to the outer end of each of the latter is attached a strip 12, which slightly overlaps the vertical edges of 60 the said partitions. Between each two adjacent partitions and behind the strips 12 in each compartment is disposed a panel 13, which may be formed of glass or other transparent material, or which may be formed of 65 wood, metal, wire-netting, or any material most suitable for the purpose. Said panels have beveled edges 14, corresponding to the angle formed by the partitions, whereby the panels are held against inward movement. 70 To the under side of the partitions is attached a bottom 15, to the edge of which are secured strips 16, that close the joints between the bottoms of the panels and the bottom 15. The panels are thus held closely in place between the partitions, but may be readily lifted 75 out to facilitate cleaning the bins or compartments.

To the bottom 15 is secured a cross-bar 17. The bottom 15 and cross-bar 17 are provided 80 with apertures that register with each other, and through said apertures is passed a headed bolt 18, over the lower threaded end of which is placed a nut 19, that is screwed up firmly against the cross-bar 17, fastening the bolt 85 rigidly to the floor 15 and cross-bar 17. The lower end of the bolt is rounded or pointed and is stepped in a step-bearing 20, seated in a suitable recess formed in the cross-bar 6.

The top of the cabinet is open, and a pivot-bolt 21 passes through an aperture formed in the cross-bar 5 and turns loosely therein, said bolt being rigidly screwed or driven in one of the partitions, as 8. The counter 22 forms a cover or top for the cabinet and is provided 95 with an approximately triangular aperture corresponding in size and shape to one of the compartments or bins, and said aperture is closed by a hinged lid 23.

It will be readily understood that the cabinet may be rotated so as to cause any one of the bins or compartments to register with the

hinged lid 23 of the counter, and by lifting the latter access is had thereto. By making the counter and cabinet-top in one, as described, no space is uselessly taken up, while 5 at the same time the counter-top may be used as usual, and also serves as a cover for the cabinet.

In Figs. 5 and 6 I have illustrated a slightly modified cabinet. In this form the cabinet 10 proper is constructed in the manner before described, excepting that in the inner and upper portion of each bin or compartment is arranged a small tray 25, and instead of the cabinet forming a part of a counter it serves 15 as a kitchen-table, the top of the cabinet forming the table-top, and the hinged lid 26 is formed of a single piece of smoothly-planed wood, which, when turned back, serves as a bread-board, while the table-top serves all the 20 useful purposes of the usual kitchen-table. The small trays are designed for the reception of coffee, salt, spices, and similar small household supplies, while the bins or compartments are used for the storage of flour, 25 meal, and other supplies of greater bulk.

In both of the forms illustrated the top of the cabinet forms a table-top, which may be used for various purposes, while the cabinet itself economizes space that would otherwise 30 be useless or useful for but few purposes.

Having described my invention, what I claim is—

1. The combination with an upright table-frame, of a rotary cabinet journaled therein 35 and provided with a plurality of radial compartments or bins open at the top, a plurality of trapezoidal trays corresponding in number to the said compartments or bins, one of said trays being arranged in the inner and upper 40 portion of each of the compartments or bins,

a table-top supported upon the top of said frame and having an aperture adapted to register with each of said compartments or bins, and a hinged lid for closing said aperture, substantially as described.

45

2. The combination with an inclosing frame, of a revolving cabinet journaled therein, and comprising two slotted partitions 8 and 9 fitted together at a right angle one to another, battens 11 secured between the inner ends of 50 said partitions, intermediate partitions 10 attached at their inner edges to said battens, a bottom 15 attached to the lower edges of said partitions, panels 13 closing the fronts of the compartments or bins, and an apertured table-top supported above said cabinet and provided with a hinged lid, substantially as described.

55

3. The combination with the inclosing frame comprising the top and bottom frames 2 and 60 3, uprights 4, and cross-bars 5 and 6, of the rotary cabinet 7 having a series of radial compartments or bins and a bottom 15, a cross-bar 17 attached to the under side of said bottom, a bolt secured in the bottom and cross-bar 17, and journaled in a step-bearing 20 seated in a recess in the cross-bar 6, a pivot-bolt 21 secured in the partition 8 and journaled loosely in the cross-bar 5, forming a pivot for the upper end of the cabinet, and 65 an apertured table-top supported on the frame 2 and provided with a hinged lid, substantially as described.

65

In testimony whereof I have hereunto set my hand in presence of two subscribing witnesses.

JOHN D. SMITH.
